UNITED STATES PATENT OFFICE.

JOSEPH H. POPE, OF SOUTH HAMILTON, MASSACHUSETTS, ASSIGNOR TO UNITED SHOE MACHINERY COMPANY, OF PATERSON, NEW JERSEY, A CORPORATION OF NEW JERSEY.

MACHINE FOR STACKING HEEL-BLANKS.

1,088,721.

Specification of Letters Patent. Patented Mar. 3, 1914.

Application filed July 6, 1909. Serial No. 506,090.

To all whom it may concern:

Be it known that I, JOSEPH H. POPE, a citizen of the United States, residing at South Hamilton, in the county of Essex and State of Massachusetts, have invented certain Improvements in Machines for Stacking Heel Blanks, of which the following description, in connection with the accompanying drawings, is a specification, like reference characters on the drawings indicating like parts in the several figures.

This invention relates to machines for stacking heel blanks.

The present embodiment of the invention is illustrated herein as an improvement upon the machine shown in a prior application for Letters Patent, Serial No. 347,540, filed December 12, 1906. As will be apparent, however, from a consideration of the construction herein shown, many features thereof may be advantageously used in connection with machines of a different type from that described in said prior application. The machine of said prior application includes a receiver which is adjustable in width to accommodate blanks of different width and a carrier which receives blanks from a heel compressor and places them on end in the receiver. The machine of the prior application also includes means for positioning the blanks upon the carrier comprising guides with which the side edges of a blank have contact. The guides are mounted upon the carrier and are arranged for adjustment laterally thereon in order to accommodate lifts varying in width.

A feature of the present invention consists in arranging for simultaneous adjustment in the side walls of the receiver and guides for positioning the blanks upon the carrier. According to the construction shown the guides are secured to the side walls of the receiver so that in adjusting the receiver a proper adjustment of the guides is effected at the same time, independent adjustment of these devices being thus rendered unnecessary.

The guides referred to are preferably connected movably with the side walls of the receiver and extend over and upon the blank-receiving surface of the carrier in order that the guides may follow the carrier in its movements and always remain in proper relation therewith for maintaining a blank in correct position to be delivered to the receiver. In the illustrated embodiment of the

invention, also, a spring or other yielding device is arranged to act on the guides in order to hold them in contact with the carrier during its movements from blank-receiving into blank-delivering position, and vice versa.

A further feature of the invention consists in means for restraining a blank from outwardly longitudinal movement upon the carrier in the movement of the carrier between its receiving position and delivering position. This feature is particularly useful where the blanks to be stacked are of considerable thickness, for example, where they are heel blanks composed of a plurality of superposed lifts. This obviates any liability of a blank being forced outwardly by the pressure applied thereto by the carrier in advancing the contents of the receiver.

Other features of the invention, the advantages of which will be apparent to one skilled in the art, will be hereinafter described and referred to in the appended claims.

In the drawings,—Figure 1 is a view in perspective of a machine constituting one embodiment of the present invention; Fig. 2 is a view in vertical longitudinal section of the machine shown in Fig. 1; Fig. 3 is a top plan view of the carrier and parts immediately adjacent thereto shown in the preceding figures.

Referring to the drawings 1 indicates the head of a compressing machine which is automatically raised and lowered as in the machine of the prior application referred to. The bracket 4 is secured to a rear face of the compressor frame, said bracket being provided with a horizontal bore in which is received a rod 6 extending rearwardly from the bracket. Hubs 10 and 12 are mounted upon the rod 6 and rigidly secured thereto. The hubs 10 and 12 are provided with upward extensions to which the plate 16 forming the bottom of the receiver is secured. The sides 18 and 20 of the receiver have secured thereto arms which are mounted upon the rod 6 and support the plates 18 and 20 in position. The lower ends of the arms are formed as collars provided with segmental beveled gears, bevel gears being arranged upon the hubs 10, 12 between and in engagement with the segmental gears. Springs 36 and 37 are provided for pressing the sides 18 and 20 toward each other.

The construction thus far particularly described is substantially the same as in the prior application referred to and need not be described more in detail. While in the prior application means are described for limiting the movement of the side walls 18 and 20 toward each other and thus determining the normal position of the side walls, in the present machine no means are provided for this purpose as I have found that a proper relative position of the side walls 18 and 20 may be conveniently secured by inserting a blank in position between the side walls preliminary to fitting the receiver.

A frame 40 is secured upon the rod 6 and is provided at its upper end with bearings for a shaft 42. Secured to the central portion of the shaft 42 is a carrier 44. The shaft 42 is provided with a quadrant at one end and a chain secured to said quadrant and to the head 1, as in the machine of the prior application.

Guides 46 and 48 are pivotally mounted upon the side walls 18 and 20, respectively, for movement in planes parallel to the planes of said walls. A pin 50 is inserted in apertures formed in the rear ends of the guides 46 and 48 and a rod 52 connects the pin 50 to one end of a spring 54, the other end of which is connected to the hub 12. It will be seen that the spring 54 applies force to the guides 46 and 48 tending to maintain them in contact with the carrier 44. The pressure of the guides 46 and 48 upon the carrier 44 also serves to depress the carrier in the downward movement of the head 1. The carrier 44 is provided with a shoulder, extending transversely across the same, formed by a removable plate 56. It will be seen from Fig. 2 that as soon as the breast edge of a blank passes beyond the rear edge of plate 56 outward longitudinal movement of the blank is prevented. It will be understood that such movement might be occasioned by the engagement of a blank upon the carrier with the endmost blank in the receiver in the upward movement of the carrier. If desired the plate 56 may be removed to provide space for lifts of increased length. In that case the shoulder formed upon the carrier 44 itself, as shown in Fig. 2, serves to prevent longitudinal movement of the lifts. The return with the carrier 44 of the blank inserted by said carrier in the receiver is prevented by vertical abutments 57 inserted in the walls 18 and 20 approximately in line with the axis of the carrier 44.

In Fig. 1 the reference numeral 58 indicates the fingers of the ejecting mechanism which push a compressed blank from the top of the top lift plate of the machine upon the carrier 44. In the ends of each finger 58 is arranged a rod 60 which is adjustable

longitudinally of the finger and held in place by a clamping screw 62. In the outer end of each rod 60 is arranged a cross bar 64 which is adjustable horizontally and transversely of the rod 60 and finger 58, said cross bar 64 being held in place by a screw 66. It will be observed that this construction permits the length of the fingers 58 to be varied. This may be desirable where a considerable change occurs in the size of the blanks being operated upon; for example where the blank is quite small the length of the fingers 58 may be increased in order to insure that the blanks will be advanced far enough by said fingers to arrive in proper position upon the carrier 44. It may also be desired to adjust the cross bars 64 transversely in order to arrange them the proper distance apart to accommodate the width of the blank.

Having described my invention, what I claim as new and desire to secure by Letters Patent of the United States is:—

1. In a machine of the class described, the combination with a receiver adjustable in width to accommodate blanks varying in width, of a carrier for supplying blanks successively to the receiver, and guides for engaging the sides of a blank to position it upon the carrier arranged for adjustment simultaneously with the receiver.

2. In a machine of the class described, the combination with a receiver having side walls arranged for relative adjustment to accommodate blanks varying in width, of a carrier for supplying blanks successively to the receiver, and guides for positioning a blank upon the carrier mounted upon said side walls of the receiver for simultaneous adjustment therewith.

3. In a machine of the class described, the combination with a receiver, of a carrier arranged for angular movement from a receiving position into a position in which it inserts a blank on edge in the receiver, and means engaging an edge of the blank for restraining the blank from longitudinal movement upon the carrier in the movement of the carrier into delivering position.

4. In a machine of the class described, the combination with a receiver of a carrier arranged for swinging movement from an approximately horizontal receiving position into a vertical position in which it inserts a blank on edge in the receiver, and means engaging an edge of the blank upon the carrier for restraining the blank from longitudinal movement in the movement of the carrier into delivering position.

5. In a machine of the class described, the combination of a receiver, a carrier arranged for movement from a receiving position into a position in which it inserts a blank on edge in the receiver, and means for restraining the blank from longitudinal movement upon

the carrier in the movement of the carrier into delivering position, said last named means being variable to accommodate blanks of different lengths.

5 6. In a machine of the class described, the combination with a receiver, of a carrier arranged for movement from a receiving position into a position in which it inserts a blank in the receiver, and guides movably connected with the side walls of the receiver and arranged to position a blank upon the carrier.

10 7. In a machine of the class described, the combination with a receiver, of a carrier arranged for swinging movement from an approximately horizontal receiving position into a vertical position in which it inserts a blank on edge in the receiver, and guides movably connected with the side walls of the receiver and arranged to rest upon the carrier and position blanks thereon prior to their insertion into the receiver.

15 8. In a machine of the class described, the combination with a receiver, of a carrier arranged for movement from a receiving position

20 into a position in which it inserts a blank in the receiver, guides movably connected with the side walls of the receiver and arranged to position a blank on the carrier, and yielding means for maintaining said guides in engagement with said carrier.

25 9. In a machine of the class described, the combination with a receiver having side walls arranged for relative lateral adjustment, of a carrier arranged for movement from a receiving position into a position for inserting blanks on edge in the receiver, and guides for positioning a blank upon the carrier movably connected with the side walls of the receiver, and arranged for adjustment therewith and also for movement with the carrier.

30 In testimony whereof I have signed my name to this specification in the presence of two subscribing witnesses.
